PC(57) **CLAIM**

The ornamental design for a cockpit user input device, as shown and described.

DESCRIPTION

The patent or application file contains a least one drawing executed in color. Copies of this patent or patent application publication with color drawing(s) will be provided by the Office upon request and payment of the necessary fee.

FIG. 1 is a front perspective view of a cockpit user input device in a center console showing our new design;

FIG. 2 is a front view thereof, with environmental structure removed for clarity of disclosure;

FIG. 3 is a back view thereof;

FIG. 4 is a first side view thereof;

FIG. 5 is a second side view thereof; and,

FIG. 6 is a top view thereof, the bottom view forming no part of the claimed design.

The broken lines illustrate structure and environment that form no part of the claimed design.
